ATTORNEY

UNITED STATES PATENT OFFICE

159,356

REFRIGERATOR TRAY

Joshua Gordon Lippincott, Scarsdale, N. Y., assignor, by mesne assignments, to Bridgeport Moulded Products, Inc., Fairfield, Conn., a corporation of Connecticut

Application August 10, 1948, Serial No. 148,026

Term of patent 14 years

(Cl. D67—3)

To all whom it may concern:

Be it known that I, Joshua Gordon Lippincott, a citizen of the United States, residing at Scarsdale, in the county of Westchester and State of New York, have invented a new, original, and ornamental Design for Refrigerator Trays, of which the following is a specification, reference being had to the accompanying drawing, forming part thereof, and in which:

The figure is a perspective view of a refrigerator tray, showing my new design.

I claim:

The ornamental design for a refrigerator tray, substantially as shown.

JOSHUA GORDON LIPPINCOTT.
